US0D1056874S

(12) **United States Design Patent** (10) Patent No.: **US D1,056,874 S**
(45) Date of Patent: ** Jan. 7, 2025

(54) **PAIR OF EARPHONES**

(71) Applicant: **SHENZHEN GRANDSUN ELECTRONIC CO., LTD.**,
Guangdong (CN)

(72) Inventors: **Jiugao Peng**, Guangdong (CN);
Haiquan Wu, Guangdong (CN);
Chuan Wang, Guangdong (CN);
Ruiwen Shi, Guangdong (CN); **Zhijun Zhang**, Guangdong (CN); **Chuanqi Zhang**, Guangdong (CN)

(73) Assignee: **Shenzhen Grandsun Electronic Co., Ltd.**, Guangdong (CN)

(**) Term: **15 Years**

(21) Appl. No.: **29/866,594**

(22) Filed: **Sep. 20, 2022**

(30) **Foreign Application Priority Data**

Jul. 27, 2022 (CN) 202230484540.7
(51) LOC (15) Cl. **14-01**
(52) U.S. Cl. **D14/223**

(57) **CLAIM**

The ornamental design for a pair of earphones as shown and described.

DESCRIPTION

FIG. 1 is a top, right, front side perspective view of an earphone of a pair of earphones showing our new design, the earphone is shown separately for ease of illustration;
FIG. 2 is a front elevation view thereof;
FIG. 3 is a rear elevation view thereof;
FIG. 4 is a left side elevation view thereof;
FIG. 5 is a right side elevation view thereof;
FIG. 6 is a top plan view thereof;
FIG. 7 is a bottom plan view thereof;
FIG. 8 is a top, right, front side perspective view of a pair of earphones thereof;
FIG. 9 is an enlarged partial view showing a part on a right side in FIG. 1;
FIG. 10 is an enlarged partial view showing a part on a left side in FIG. 3; and,
FIG. 11 is an enlarged partial view showing a part in a middle in FIG. 5.
The dot dash broken line surrounding the portions of the pair of earphones in FIGS. 1, 3, 5 and illustrated in the enlarged views of FIGS. 9, 10, 11 form no part of the claimed design.
